UNITED STATES PATENT OFFICE

RALPH McCARTHY, OF ELGIN, ILLINOIS

CLEANER FOR FURNACES, BOILERS, AND THE LIKE

Application filed May 7, 1930. Serial No. 450,336.

This invention relates to cleaners for furnaces, boilers and the like, and more in particular to a construction of cleaner and scraper therefor, and adapted for cleaning and scraping flues, radiators, and various pipes and passages of furnaces. In view of the numerous curves, angles and relatively inaccessible parts of a furnace, and especially is this true in the furnace, radiator and smoke pipe, it has always been extremely difficult and frequently impossible to clean the same.

Among the objects of the invention are to provide a cleaner adapted to thoroughly clean and scrape furnace flues, radiators, smoke pipes, boilers and other pipes or passages where soot, dust, carbon, scale and other foreign particles and material may collect or adhere thereto. Due to the curvature of such flues, radiators, and other passages, and since such passages are provided with a minimum number of openings or clean-out doors for securing access thereto, it has always been an extremely difficult matter, and generally impossible, to thoroughly clean the same, especially in and beyond the curved portions. The present invention comprehends the provision of cleaning mechanism provided with a flexible shaft of any desired length, that may be inserted into a pipe, flue, radiator or other passage of any configuration and curvature, and be forced therethrough by the operator.

Another object of the invention is to provide a means for scraping and withdrawing the accumulated soot, carbon, dust or other foreign material after the same has been dislodged by the cleaning mechanism. This scraping mechanism further provides means for anchoring and centering the mechanism for dislodging the foreign particles. The invention further comprehends arm members for centering the cleaning and scraping mechanism whenever the passage to be cleaned is of relatively great size or diameter.

Further objects are to provide a construction of maximum simplicity, efficiency, economy, and ease of assembly, adjustment and detachment, one that may be readily inserted and easily withdrawn from the structure to be cleaned, and such further objects, advantages and capabilities as will later more fully appear, and are inherently possessed thereby.

The invention further resides in the combi-

nation, construction, and arrangements of parts illustrated in the accompanying drawing, and while I have shown therein a preferred embodiment, it is to be understood that the same is susceptible of modification and change, and comprehends other details, arrangements of parts, features and constructions, without departing from the spirit of my invention.

Referring to the drawing:

Fig. 1 is a fragmentary view, part in side elevation, and part in vertical cross section, taken through a furnace pipe and showing the cleaning mechanism in operation.

Fig. 2 is a view in vertical cross section taken in a plane represented by the line 2-2 of Fig. 1.

Fig. 3 is a view in vertical cross section through the dished plate and showing the means of attaching the flexible shaft and chains or weighted members to the plate.

Fig. 4 is a view similar to Fig. 2, but disclosing centering arms or projections attached to the edge of the plate member.

Referring more particularly to the drawing, the embodiment selected to illustrate the invention is shown as comprising a plate or central member 1, to which is attached a flexible shaft or spring rod 2 by means of a bolt or the like 3 and nut 4. This flexible shaft or spring rod may be of any desired length, depending upon the use to which the same is put and the length of the passage to be cleaned. This shaft is adapted to be rotated by means of a handle or brace 5 having a sleeve 6 adapted to be grasped by the operator. This brace or crank member 5 when turned by the operator, gives a rotary motion to the shaft 2 and plate or disc 1.

The plate member or disc is provided with a tapered flange 7 to which is connected a plurality of chains or other weighted members 8 having at their end additional weight members 9. These chains and weight members are adapted to be impinged against the inner surface of a pipe, radiator, flue or other passage in or connected to a furnace or boiler. As shown in Figs. 1, 2 and 4, the cleaning mechanism is disclosed as operating in a pipe 10 of a furnace.

In view of the shaft being flexible, the cleaner may be projected through and rotated in a passage of any shape or curvature, Fig. 1 disclosing in dotted outline, the position which the flexible shaft 2 and plate or

disc member 1 will assume when it is propelled through a curved pipe. The disc or plate member and its attached chains or weighted members can be readily inserted through a clean-out door or other closure in the pipe, radiator or other passage which is desired to be cleaned. As the shaft and disc or plate member are rotated, the chains and the weights attached thereto are thrown outwardly by centrifugal force and impinge against the sides of the passage being cleaned, dislodging therefrom any soot, dust, or other foreign particles which may adhere thereto or be collected therein. During the cleaning of the passage, the dislodged particles will necessarily drop by gravity to the lower portion of the passage, and as the cleaner is being withdrawn, the disc or plate member, due to its dished or concaved construction, will scrape and remove the collected particles.

During the rotation of the flexible rod or shaft 2, the plate or disc is maintained in substantially a central position within the pipe or passage, but when rotation of this flexible rod is stopped, the disc or plate is dropped to the bottom or lower inner surface of the pipe or passage being cleaned, due to the resiliency of the shaft. The soot or other foreign materials which have been dislodged or removed by the impingement of the weighted members, are then scraped or taken out upon withdrawing the dished plate of the cleaner from the pipe or passage of the structure being cleaned.

In Fig. 1 is disclosed a smoke pipe 10 connected to a pipe 11 leading from a furnace or the like, and which pipe 11 is provided with a check door 12. In this figure, the cleaner is shown as having been applied through a clean-out door (not shown), although it is to be understood that the same can be readily inserted through the opening covered by the door 12 into the pipe 11, and from there projected through either the pipe 10 or through the pipe 11 leading to the furnace.

Whenever the passage to be cleaned is of relatively great diameter or size, the disc or plate member 1 may be provided with arm members or projections 13 adapted to align and center the disc 1 in the passage. Ordinarily such arm members or projections are not necessary and may be dispensed with.

From the above description and the disclosure in the drawing, it will be readily seen that I have provided a cleaner which is simple in construction and highly efficient in operation, and not only has the function of dislodging the foreign particles, but is adapted to remove the same as well. By reason of the flexible shaft, the cleaner may be projected completely around the radiator

of the furnace and thoroughly clean the same.

Having thus disclosed my invention, I claim:

1. A cleaner for furnaces, boilers and the like, comprising a dished plate member, a flexible shaft attached thereto and adapted to be extended to all parts of the structure regardless of bends or turns, weighted members swingably attached to said plate member, and means for giving said plate member and weighted members a rotary movement whereby said weighted members will strike the inner walls of the structure being cleaned to dislodge the soot and other foreign particles, said plate member being dished toward the operator and adapted to contact the lower inner surface of the structure being cleaned to scrape and remove the accumulated soot and foreign particles when the cleaner is being withdrawn. 70

2. A cleaner for furnaces, boilers and the like, comprising a dished plate member, weighted members swingably attached to said plate member, a flexible shaft connected to and extending perpendicular from said plate member and adapted to be extended to all parts of the structure regardless of bends or turns, and means for giving said shaft, plate member and weighted members a rotary movement whereby said weighted members will strike the inner walls of the structure being cleaned to dislodge the soot and other foreign particles, said plate member being dished toward the operator and adapted to contact the lower inner surface of the structure being cleaned to scrape and remove the accumulated soot and foreign particles when the cleaner is being withdrawn. 75

3. A cleaner for furnaces, boilers and the like, comprising a plate member, chains connected to the periphery of said member, a shaft connected centrally to said member, means for rotating said shaft and plate member, and means on said plate member for guiding and centering the same as it is being rotated. 80

4. A cleaner for furnaces, boilers and the like, comprising a dished member, weighted members connected thereto, and means for rotating said dished member and weighted members whereby said members are adapted to be projected against the sides of a passage to dislodge and remove accumulated foreign particles, said dished member being dished toward the operator and adapted to contact the lower inner surface of the passage for gathering and removing said accumulated particles as said cleaner is being withdrawn. 110

In witness whereof, I hereunto subscribe my name to this specification.

RALPH McCARTHY.
